8 Claims. (Cl. 103—136)

1

This invention relates to an improved rotary pump and refers especially to rotary pumps of the type wherein a rotor is eccentrically mounted within a casing having inlet and outlet ports communicating with feed and delivery pipes.

A rotary pump has previously been devised which comprises essentially a casing, a circular chamber in the casing, inlet and outlet ports communicating with the chamber, a rotor mounted eccentrically and rotatably in the chamber, a plurality of radial or approximately radial recesses in the rotor, a roller or cylindrical piston in each recess, and a channel or channels in the leading face of each recess for admitting liquid under pressure to the recess in order to maintain the rollers or pistons in contact with the wall of the chamber when the rotor is rotated.

More specifically, the pump (which is described in the prior Australian Patent No. 121563) comprises a casing, a circular chamber in the casing, inlet and outlet ports in the casing and communicating with the chamber, said inlet and outlet ports being substantially diametrically opposite to one another, a cylindrical rotor mounted eccentrically in the chamber and arranged so as to be contiguous with or close to the peripheral wall of the chamber at a point between the inlet and outlet ports, the point of greatest radial distance between the periphery of the rotor and the peripheral wall of the chamber being located substantially midway between the inlet and outlet ports on the opposite side of the chamber from the point at which the rotor is closest to the peripheral wall of the chamber, a plurality of radial or approximately radial recesses in the rotor, a cylindrical roller fitting neatly within each recess and rotatable and radially movable therein, the diameter of each roller being at least twice the maximum distance between the rotor and the peripheral wall of the chamber and the depth of each recess being slightly greater than the diameter of a roller, and a channel or channels in the leading face of each recess to admit liquid under pressure to the inner end of the recess and thereby assist in maintaining the rollers in contact with the wall of the chamber.

The liquid under pressure in the portion of the crescent-shaped space between a roller and the outlet port is admitted through the channel or channels to the inner end of the recess in which the roller is fitted and exerts an outward radial pressure on the inner periphery of the roller which exceeds the inward radial pressure of the liquid against the outer periphery of the roller,

2

thereby assisting to maintain the roller in contact with the peripheral wall of the chamber.

Rotary pumps of the type above described are subject to certain disadvantages. In the first place, after the leading edge of a recess moves past the point on the inner periphery of the casing at which the rotor is closest to the periphery of the casing (hereinafter termed the "midpoint"), the said leading edge moves away from the periphery and until the following edge of the recess reaches the mid-point the effectiveness of the seal between the inlet and outlet chambers is greatly reduced.

When the recess reaches the outlet port, the pressure on both sides of the roller is equalised and the roller is maintained against the casing by centrifugal force. However, when the roller reaches the end of the outlet port nearest the mid-point, the roller is forced into the recess in the rotor by the pressure of liquid, and thus ceases to create an effective seal between the rotor and the casing. The roller remains in this position until the following edge of its recess reaches the mid-point, thereby sealing off the recess from the outlet chamber of the pump and thus relieving the pressure on the outer face of the roller. This causes the roller to be suddenly thrown outwards against the wall of the casing by centrifugal force, which results in undesirable noise and wear.

It is an object of this invention to provide improvements in a rotary pump of the kind described which will substantially overcome the abovementioned disadvantages and will enable the construction of a pump which is economical to build and is thoroughly efficient in operation.

A feature of the invention consists in providing an arcuate recess in the peripheral wall of the casing at or adjacent to the point of closest approach at which the rotor is closest to the periphery of the rotor chamber, the curvature of such recess being substantially equivalent to that of the rotor and the latter being mounted in the casing so that its periphery rotates in fluid-tight running contact with the periphery of such recess.

The arcuate recess is preferably of width equal to that of the internal periphery of the casing and extends between points on opposite sides of the said point of closest approach, the centre of curvature of said recess being spaced a short distance towards the point of closest approach from the centre of curvature of the internal periphery of the casing, and the length of said recess being greater than the distance between the leading and following edges of each recess in the rotor.

The centre of curvature of the arcuate recess is preferably coincident with the centre of the rotor shaft so that both the leading and following edges of the recesses in the rotor are in contact with or in close proximity to the periphery of the casing over the full length of the said recess.

A further feature of the invention resides in the provision of means for admitting fluid under pressure to the inner face of each roller when the latter is in the region of the point of closest approach, and preferably when the roller is approaching the point of closest approach, whereby the roller will be forced outwards against the periphery of the casing by such fluid pressure and by centrifugal force so as to assist in maintaining the seal between the inlet and outlet chambers of the pump. This means may comprise a port, channel or groove in the end of the casing or in the end-plate and disposed so as to place the channel in the leading face of the recess and/or the space between the leading edge of the recess and the roller in communication with the outlet chamber of the pump when the roller is in the vicinity of or approaching the point of closest approach.

The rotor may be provided with two, three or any other appropriate number of rollers and recesses therefor, although three are preferred. The ports or channels for ingress and egress of fluid to and from the rotor chamber may be formed in one or both ends of the casing.

Other objects and features of the invention will become apparent from the ensuing description of the form of the invention illustrated in the accompanying drawings, wherein:

Figure 1 is a view in end elevation of a rotary pump constructed in accordance with the invention, an end plate having been removed.

Figure 2 is a view in side elevation partly in section taken on the line 2-2 of Figure 1.

Figure 3 is a view in end elevation of the rotor.

Figure 4 is a view in section on the line 4-4 of Figure 3.

Figure 5 is a view of one of the rollers.

Figure 6 is a view in end elevation of the casing, the rotor and rollers having been removed.

Figure 7 is a view in section taken on the line 7-7 of Figure 6.

Figures 8 and 9 are views of the pump showing the rotor in successive positions, and

Figure 10 is a diagrammatic view to an enlarged scale of the upper end of the casing.

Referring to the drawings, wherein the same reference numerals indicate like or corresponding parts, the reference numeral 20 indicates the cylindrical casing of a rotary pump. The casing 20 is provided with open ends which are adapted to be closed by end plates 21, 22 secured to the casing 20 by bolts 23. The casing 20 is supported on a stand 24 and is furnished with inlet and outlet chambers formed in bosses 25, 26 disposed on opposite sides of the casing and integral therewith. Flanges 27 are provided on the bosses 25, 26 for attachment of inlet and outlet pipes thereto.

The inlet chamber communicates through ports 28 in the casing 20 with chambers 29 in the end plates 21, 22 and thence through inlet ports 30, 31 with the interior of the casing 20. The outlet chamber connects through ports 32 in the casing 20 with chambers 33 in the end plates, and the chambers 33 communicate through outlet ports 34, 35 with the interior of the casing.

A rotor 36 is eccentrically and rotatably mounted within the casing 20. The rotor 36 is keyed

to a shaft 37 which is carried in ball bearings 38 mounted in the end plates 21, 22. The bearings 38 are retained in position by cover plates 39. Rotation is imparted to the shaft by any suitable source of power (not shown). Suitable gland means (not shown) are provided to prevent leakage of fluid between the bearings and the shaft 37.

The casing 20 can be of any approved width and diameter and the clearance between the ends of the rotor 36 and the ends of the casing 20 is just sufficient to permit freedom of rotation of the rotor 36 within the rotor chamber.

Three equally spaced radial recesses 40 are formed in the rotor 36 in which rollers 41 are fitted, the said rollers being cylindrical in shape and being capable of radial movement in the recesses 40. The inner ends of the recesses 40 are semi-cylindrical to accommodate the rollers 41 when they are in their innermost positions. Channels 42 are formed in the leading and inner faces of the recesses 40 at each side of each recess 40 (see Figure 4). The channels 42 are in communication with arcuate ports 43 in the rotor 36 on each end thereof, the said ports 43 extending in opposite directions from the inner ends of the recesses 40.

An arcuate recess 44 (see Figure 10) is formed in the periphery of the casing 20 at the upper end thereof adjacent to the point at which the rotor 36 is closest to the said periphery. The recess 44 extends from point X to point Y on the casing as shown in Figure 10, and is of the same curvature as that of the rotor 36. The shaft 37 is so mounted in the casing 20 that the periphery of the rotor 36 moves in fluid tight running contact with the peripheral wall of the recess 44 from Y to X, (the direction of rotation being as shown in Figure 1). The length of the recess 44, that is the distance from X to Y, is greater than the width of one of the recesses 40, so that the following edge 45 of one of said recesses 40 enters the recess 44 before the leading edge 46 has left the recess 44. Thus, even if the roller 41 is not in contact with the periphery of the casing at this point, an effective seal is created between the rotor 36 and the periphery of the casing 20 in the vicinity of the point of closest approach. This seal is rendered more effective owing to the means employed (as hereinafter described) for causing the rollers 41 to be moved outwardly against the periphery of the casing 20 as they approach the point of closest approach.

The outer inlet ports 30 are disposed adjacent to the periphery of the rotor chamber and are shaped to increase in width from their upper or rear ends to their lower or forward ends. The inner inlet ports 31 are adapted to communicate with the inner ends of the recesses 40 in the rotor as the said recesses pass thereover, and the said ports 31 are located so that their upper or rear ends are brought into communication with a recess 40 when the leading edge of said recess 40 has passed the end X of the arcuate recess 44 and so that their lower or forward ends are cut off from communication with the recess 40 when the lower or forward ends of the outer inlet ports 30 are closed by the roller 41 in the said recess.

The said outer inlet ports 30 are shaped so as not to substantially exceed in radial extent the crescent-shaped recess between the rotor and the periphery of the casing 20, so that the said ports are closed by the rollers 41 as they pass thereover. Fluid is thus admitted to the rotor chamber in advance of the rollers 41 but the ports 30 are

closed by the rollers 41 before the outlet ports are in communication with the corresponding recesses 40.

The outer outlet ports 35 are located adjacent to the periphery of the casing 20 and are shaped to decrease in radial extent from their lower or rear ends to their upper or forward ends. The inner outlet ports 34 are arcuate in shape and their lower or rear ends are disposed so as to communicate with the inner end of a recess 40 in the rotor 36 immediately after the inlet ports 30 have been closed by the roller 41 in the said recess 40. The upper or forward ends of the outlet ports 34 are disposed so that they are in communication with the inner ends of the recesses 40 in the rotor until shortly after the following edge of the recess 40 enters the arcuate recess 44 and are cut off from communication with the recess 40 shortly before the leading edge of the recess 40 leaves the arcuate recess 44.

Thus fluid under pressure is admitted to the inner ends of the recesses 40 over a maximum angular distance, and thereby assists in maintaining the rollers 41 against the peripheral wall of the casing during rotation of the rotor 36.

The successive positions of the rollers 41 and recesses 40 during rotation of the rotor are shown at A, B and C in Figures 1, 8 and 9. In Figure 1 the roller in position A is at the point of closest approach and is functioning to seal the outlet from the inlet at this point. The seal is also effected by the leading and following edges 46, 45 of the recess 40 in this position being in contact with or in close proximity to the periphery of the casing 20 between the points X and Y (see Figure 10).

When the roller 41 reaches position A in Figure 8, fluid is admitted to the recess 40 through the inlet ports 30 and 31 and, at the same time, the roller commences to move outwardly in the recess 40 due to centrifugal force acting thereon and to the divergence between the periphery of the rotor and the periphery of the casing. The fluid admitted through the inlet ports 30, 31 is moved around ahead of the roller 41 by such roller and when the roller reaches position B in Figure 1, the inlet ports 30, 31 are cut off from the recess 40, so that a positive transfer to the outlet ports of the fluid admitted through the inlet ports is effected.

At position B in Figure 8, the inner end of the recess 40 is in communication with the inner outlet port 34 so that pressure is applied to the inner face of the roller to maintain it against the periphery of the casing. Egress of fluid through the outlet ports 34 and 35 occurs owing to the fluid in front of the roller being forced outwardly through said outlet ports as the roller moves from position B in Figure 1 to position C in Figure 9. The outlet port 34 remains in communication with the inner end of the recess 40 after the leading edge 46 of such recess enters the arcuate recess 44 and is cut off therefrom shortly before the side leading edge 46 leaves the arcuate recess 44, so that fluid pressure acts on the inner face of the roller until after it passes the point of closest approach.

It will be understood that the pump may be constructed so that the point of closest approach, that is the point at which the rotor is closest to the peripheral wall of the chamber is located at the top or bottom or at either side of the pump when the latter is erected in its running position.

In the specification and claims hereof the "mid-point" of the peripheral wall of the rotor chamber

means that point at which the rotor is closest to the said wall.

It will also be appreciated that end plates may be provided at one or both ends of the casing, and that the shaft may be supported in bearings at one end only of the casing instead of at both ends thereof.

I claim:

1. A rotary pump comprising a casing, a circular rotor chamber in the casing, inlet and outlet ports in the casing communicating with the rotor chamber, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid-tight running contact with the peripheral wall of said arcuate recess, the width of the arcuate recess being substantially equal to that of the rotor chamber and the centres of curvature of the arcuate recess and the rotor being coincidental, the length of the arcuate recess being greater than the distance between the leading and the following edges of a radial recess, and the outlet port being in communication with the inner end of each radial recess as it approaches the said point of closest approach and remaining in communication with said radial recess until shortly before the leading edge of said radial recess leaves the said arcuate recess.

2. A rotary pump comprising a casing, a circular rotor chamber in the casing, inlet and outlet ports in the casing communicating with the rotor chamber, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid tight running contact with the peripheral wall of said arcuate recess, the centre of curvature of the arcuate recess being coincidental with that of the rotor, and the length of the arcuate recess being greater than the distance between the leading and following edges of a radial recess in the rotor, and the outlet port being in communication with the inner end of each radial recess until after the following edge of the radial recess has entered the arcuate recess and being cut off from communication with the said inner end before the leading edge of the radial recess leaves the arcuate recess.

3. A rotary pump comprising a casing, a circular rotor chamber in the casing, inlet and outlet ports in the casing communicating with the rotor chamber, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is

closest to the periphery of the rotor chamber, the curvature of said arcuate recess being substantially equal to that of the periphery of the rotor and the said rotor being in fluid tight running contact with the peripheral wall of said arcuate recess, the width of the arcuate recess being substantially equal to that of the rotor chamber and the centres of curvature of the arcuate recess and the rotor being coincidental, the length of the arcuate recess being greater than the distance between the leading and following edges of a radial recess, the outlet port being in communication with the inner end of each radial recess until after the following edge of the radial recess has entered the arcuate recess and being cut off from communication with the said inner end before the leading edge of the radial recess leaves the arcuate recess, and the inlet port being in communication with each radial recess in the rotor shortly after the leading edge of such radial recess leaves the arcuate recess in the casing.

4. A rotary pump comprising a casing, a circular rotor chamber in the casing, inlet and outlet ports in the casing communicating with the rotor chamber, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid tight running contact with the peripheral wall of said arcuate recess, the width of the arcuate recess being substantially equal to that of the rotor chamber and the centres of curvature of the arcuate recess and the rotor being coincidental, the length of the arcuate recess being greater than the distance between the leading and following edges of a radial recess, the outlet port being in communication with the inner end of each radial recess until after the following edge of the radial recess has entered the arcuate recess and being cut off from communication with the said inner end before the leading edge of the radial recess leaves the arcuate recess, the inlet port being in communication with each radial recess in the rotor shortly after the leading edge of such radial recess leaves the arcuate recess in the casing, and the outlet port being in communication with the inner end of each radial recess in the rotor shortly after the said radial recess is cut off from communication with the inlet port.

5. A rotary pump comprising a casing, a circular rotor chamber in the casing, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid tight running contact with the peripheral wall of said arcuate recess, the width of the arcuate recess being substantially equal to that of the rotor chamber and the centres of curvature of the arcu-

ate recess and the rotor being coincidental, the length of the arcuate recess being greater than the distance between the leading and following edges of a radial recess, inner and outer inlet ports in the end of the casing, and inner and outer outlet ports in the end of the casing, the forward end of the inner outlet port communicating with the inner end of each radial recess until the following edge of said radial recess has entered the arcuate recess and being cut off from communication with the said inner end of said radial recess before the leading edge of said radial recess leaves the arcuate recess.

6. A rotary pump comprising a casing, a circular rotor chamber in the casing, a rotor eccentrically and rotatably mounted in the rotor chamber, radial recesses in the rotor, each of said radial recesses having a leading edge and a following edge, channels formed in the leading and inner faces of the radial recesses, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid tight running contact with the peripheral wall of said arcuate recess, the width of the arcuate recess being substantially equal to that of the rotor chamber and the centres of curvature of the arcuate recess and the rotor being coincidental, the length of the arcuate recess being greater than the distance between the leading and following edges of a radial recess, inner and outer inlet ports in the end of the casing and inner and outer outlet ports in the end of the casing, the forward end of the inner outlet port communicating with the inner end of each radial recess until the following edge of said radial recess has entered the arcuate recess and being cut off from communication with the said inner end of said radial recess before the leading edge of said radial recess leaves the arcuate recess, and the rear end of the inner outlet port communicating with the inner end of each radial recess shortly after the latter is cut off from communication with the inlet ports.

7. A rotary pump comprising a casing, a circular rotor chamber in the casing, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid tight running contact with the peripheral wall of said arcuate recess, the width of the arcuate recess being substantially equal to that of the rotor chamber and the centres of curvature of the arcuate recess and the rotor being coincidental, the length of the arcuate recess being greater than the distance between the leading and following edges of a radial recess, inner and outer inlet ports in the end of the casing, and inner and outer outlet ports in the end of the casing, the outer inlet port not substantially exceeding in radial extent that of the crescent-shaped space between the rotor and the periphery of the casing, the outer outlet port being adjacent to the periph-

ery of the casing, and the forward end of the inner outlet port communicating with the inner end of each radial recess until shortly before the leading edge of said radial recess leaves the arcuate recess.

8. A rotary pump comprising a casing, a circular rotor chamber in the casing, a rotor eccentrically and rotatably mounted in the rotor chamber, radial recesses in the rotor, each of said radial recesses having a leading edge and a following edge, rollers fitted in the radial recesses and capable of radial movement therein, an arcuate recess in the periphery of the rotor chamber adjacent to the point of closest approach at which the rotor is closest to the periphery of the rotor chamber, the curvature of said arcuate recess being substantially equal to that of the periphery of the rotor and the said rotor being in fluid tight running contact with the peripheral wall of said arcuate recess, the width of the arcuate recess being substantially equal to that of the rotor chamber and the centres of curvature of the arcuate recess and the rotor being coincidental, the length of the arcuate recess being greater than the distance between the leading and following edges of a radial recess, inner and outer inlet ports in the end of the casing and inner and outer outlet ports in the end of the casing, the forward end of the inner outlet port communicating with

5 the inner end of each radial recess until the following edge of said radial recess has entered the arcuate recess and is cut off from communication with the radial recess before the leading edge of said radial recess leaves the arcuate recess, the outer inlet port not substantially exceeding in radial extent that of the crescent-shaped space between the rotor and the periphery of the casing, the outer outlet port being adjacent to the periphery of the casing, and the forward end of the inner outlet port communicating with the inner end of each radial recess until shortly before the leading edge of said radial recess leaves the arcuate recess, and the rear end of the inner outlet port communicating with the inner end of each radial recess shortly after the latter is cut off from communication with the inlet ports.
